UNITED STATES PATENT OFFICE.

EARLE A. CLARK, OF TULSA, OKLAHOMA.

METER TOP AND INDEX BOX.

Application filed January 5, 1924. Serial No. 684,540.

My invention relates to new and useful improvements in combined top and index boxes for gas meters, and has for its object to provide a device which is economical to manufacture, the index box and the top being made in one casting.

Another object of my invention is to provide a water tight cover for meters, and to do away with the gaskets around the index box, which are necessary in the constructions now in use, and which rapidly deteriorate and become ineffectual.

With the above and other objects in view, which will appear as the description proceeds, my invention consists in the novel features herein set forth, illustrated in the accompanying drawing and more particularly pointed out in the appended claim.

Referring to the drawing; Fig. 1 is a plan view of my combined meter top and index box.

Fig. 2 is a sectional view taken on line 2—2 of Fig. 1, showing the integral casting.

Fig. 3 is a side view, and Fig. 4 is a view of the bottom showing the plate which encloses the index box.

In the drawing numerals of like character designate similar parts throughout the several views.

1 designates the main body portion of my improved top, being provided around its edges with a plurality of apertures 2 adapted to receive bolts or screws 3, which secure the top to the meter portion.

Centrally of the top, I provide an index box 4, integral therewith and preferably cylindrical, being open at its upper extremity and adapted to receive a glass 5, to enable the index 6 to be seen.

At the base of the index box and integral with the top and box, are a plurality of lugs 7, interiorly screw threaded, and adapted to receive screws 8, which secure the plate 9 to the bottom of the index box, as shown in Fig. 4.

The mechanism of the index box and meter may be of the usual construction and forms no part of my invention.

On either side of the index box 4, and also integral with the top, I provide hollow portions 10, which serve as gas inlet and outlet, threaded at their upper extremities to receive nuts 11, for holding the connecting elbows 12 in place, said elbows serving as connections to the gas line.

It will be noted that by my invention, I have produced a meter top and index box consisting practically of one casting and which is simple, inexpensive and durable, and avoids the necessity of gaskets and screws between the index box and the top, thereby adding to the safety of the device, as the escape of gas is precluded.

From the foregoing, it is believed that my invention can be clearly understood without further description, and it may be stated that numerous changes may be made in the details of construction, without departing from the spirit of the invention as disclosed in the following claim.

What I claim and desire to secure by Letters Patent is:—

A meter top comprising a body portion provided at its outer extremities with an apertured flange adapted to receive bolts, 75 unobstructed vertically extending tubular members serving as inlet and outlet, integral with said body portion and located centrally of the longitudinal extremities thereof, connecting elbows removably mounted at the 80 upper extremities of said tubular members, an upwardly extending hollow index box provided with a transparent upper face between said tubular members, spaced apart therefrom and also integral with said body 85 portion, said index box being provided on its under side with a plurality of threaded apertures, and a plate provided with corresponding apertures and adapted to receive screws for securing the same rigidly against 90 the under side of said index box to enclose the mechanism within the same.

In testimony whereof I affix my signature.

EARLE A. CLARK.
